UNITED STATES PATENT OFFICE.

DONALD S. CONNELLY, OF WOOSTER, OHIO, ASSIGNOR TO THE SAFETY STAIR TREAD COMPANY, OF WOOSTER, OHIO, A CORPORATION OF OHIO.

SANITARY COVE FOR FLOOR COVERINGS.

Application filed June 20, 1928. Serial No. 286,862.

My invention relates to sanitary coves for floor coverings, which are particularly adapted for providing a combined finishing member for the intersection of a floor and a 5 side wall, and for protecting and providing a sanitary finishing joint for the side edges of the floor covering, such as linoleum, composition, cork tile, rubber tile, and similar materials, which when used on floors, are 10 difficult to finish in a sanitary and sightly manner at their juncture with the side wall.

The objects of the present improvements include the provision of a cove which in one form may be used either in connection with 15 an original floor covering, or in another form in connection with a floor covering which has been laid directly over an original worn out floor covering which may already be provided with a cove.

20 These and ancillary objects are attained in a cove member whose construction and arrangement is hereinafter set forth in detail and claimed, and which may be stated in general terms as including a preferably integral structure having faces adapted for 25 abutment against a floor and wall at the intersection thereof or against a cove laid thereover, and faces providing an interlocking engagement for the side edges of a floor 30 covering.

Preferred embodiments of the present improvements are illustrated in the accompanying drawings forming part hereof, in which

35 Figure 1 is a fragmentary oblique perspective view illustrating one embodiment of my improved sanitary cove, as installed with an original floor covering;

40 Fig. 2, a detached fragmentary oblique perspective view of the cove illustrated in Fig. 1;

Fig. 3, a fragmentary oblique perspective view illustrating another embodiment of my improved cove as installed on a subfloor, which may be a worn out original floor covering, having an original cove; and

45 Fig. 4, a detached fragmentary oblique perspective view of my improved cove of Fig. 3.

Similar numerals refer to similar parts 50 throughout the several views.

The embodiment of my improved cove indicated generally at 10 in Figs. 1 and 2 includes a preferably integral structure which may preferably be made by extruding brass, 55 aluminum, or similar material, or which

may be formed in any well known manner from any other desired material having the required characteristics of strength and rigidity.

The cove 10 includes a normally bottom 60 plane face 11, and a normally side plane face 12 perpendicular to the face 11, and meeting the face 11 at the corner 13.

The bottom face 11 preferably comprises the lower face of a securing flange 14 outwardly protruding from the corner 13. The upper face 15 of the securing flange is preferably angular with the lower face 11, thus tapering the securing flange 14 to a relatively thin outer edge 16.

70 The securing flange is provided with a plurality of suitably spaced and preferably countersunk apertures 17 through which screws or nails may be passed for fastening the cove to the floor.

75 The side face 12 of the cove comprises the side face of an upwardly protruding protecting flange 18 which preferably includes an upper preferably curved cove face 19 extending from the upper edge 20 of the protecting flange 18 downwardly to an edge 21 located intermediate the edges 20 and 16.

80 The edge 21 is preferably the outer edge of a laterally extending tongue 22 overhanging the securing flange 14 at a distance there- 85 above equal to or slightly greater than the depth of a usual floor covering, thereby providing an interlocking engaging notch 23 for the side edge of a floor covering.

85 In use, as illustrated in Fig. 1, the cove 90 10 is secured so that its outer faces 11 and 12 abut the floor 24 and a side wall 25 at the intersection thereof, and the side edge 26 of the floor covering 27 is inserted into the notch 23, and the upper downwardly curved 95 surface of the face 19, thus forms a sanitary connecting surface between the outer surfaces of the floor covering 27 and the wall 25, and the side edge 26 of the floor covering is adequately protected by the overhanging 100 tongue 22.

105 The embodiment of my improved cove indicated generally at 110 in Figs. 3 and 4 includes a preferably integral structure which may preferably be made by extruding brass, aluminum, or similar material, or which may be formed in a well known manner from any other desired material having the required characteristics of strength and rigidity.

The cove 110 includes a normally bottom plane face 111, and a normally side curved face 112, extending tangentially from the plane face 111.

5 The bottom face 111 preferably comprises the lower face of a securing flange 114, the upper face 115 of which is preferably angular with the lower face 111, thus tapering the securing flange 114 to a relatively thin outer 10 edge 116.

The securing flange is provided with a plurality of suitably spaced and preferably countersunk apertures 117 through which screws or nails may be passed for fastening 15 the cove to the floor.

The curved side face 112 of the cove comprises the side face of a curved upwardly protruding protecting flange 118 which preferably includes an upper cove face 119 extending from the upper outer edge 120 of the protecting flange 118 to an edge 121 located intermediate the edges 120 and 116.

The edge 121 is preferably the outer edge of a laterally extending tongue 122 overhanging the inner upwardly curved end of the upper surface 115 of the securing flange 114.

30 The lower face of the tongue 122 is preferably an angled face 122' extending from the edge 119 downwardly and towards the edge 120, to meet the upwardly curved inner end of the upper face 115 forming the angled notch 123 whereby an interlocking engagement is provided for the side edge of 35 a floor covering.

The cove 110 is particularly designed for

use in connection with recovering a floor 124 which may have a subfloor 124' thereon comprising an original floor cover, and the original floor covering being originally provided at its side edges with a cove 130 having a curved outer surface 131 extending between the floor covering 124' and the upwardly extending outer surface 132 of the cove 130.

40 The curved side face 112 fits the curved surface 130 of the original cove, and the improved cove 110 is thus secured as illustrated in Fig. 3 with the surfaces 112 and 131 in abutment, and the side edge 126 of the new floor covering 127 is engaged by the tongue 122, thus forming a sanitary connecting surface between the outer surfaces of the floor covering 127 and the original cove 130, and the side edge 126 of the new 50 floor covering is adequately protected by the overhanging tongue 122.

45 I claim:

A cove including faces adapted for abutment against floor and wall faces, faces providing an interlocking engagement for the side edges of a floor covering, and a cove face, a floor abutment face and an interlocking engagement face forming a securing flange for connection with a floor, and an interlocking engagement face and the cove face forming a tongue overlapping the edge of a floor covering engaged by the interlocking engagement faces.

55 In testimony that I claim the above, I have hereunto subscribed my name.

60 DONALD S. CONNELLY.
